UNITED STATES PATENT OFFICE.

JOHN O. WOODSOME, OF NEW YORK, N. Y.

STEAM-CIRCULATING SYSTEM FOR DRIERS.

Application filed December 16, 1926. Serial No. 155,180.

This invention relates to a steam circulating system for driers and more particularly for paper making machine driers.

In paper making machine steam drier systems one of the most important provisions necessary for efficient and economical use of the steam is the provision for rapid circulating of the steam through the drying cylinders without permitting appreciable loss through the escape of uncondensed steam. The use of low pressure steam and low back pressures on the driers also increases the economy of the system.

In my co-pending application, Steam circulating system for driers, Serial No. 116,307, filed June 16, 1926, I have described and claimed one type of drying system in which Venturi type fittings are used. The present application is a division of that application showing a modified type of circulating system.

It is therefore an object of this invention to provide a steam circulating system for paper machine driers, wherein a rapid circulation of steam through the driers is effected by the use of Venturi type jet pressures and circulators and wherein loss through the escape from the driers of uncondensed steam is prevented by the use of nozzle separators.

It is a further important object of my invention to provide a steam circulating system for paper machine driers, wherein both high and low pressure steam may be used in connection with jet compressors of the Venturi type to effect rapid circulation of the steam and wherein means are provided for the reduction of the back pressure on the driers.

Other and further important objects of this invention will be apparent from the disclosures in the specification and the accompanying drawings.

This invention (in a preferred form) is illustrated in the drawings and hereinafter more fully described.

In the drawings:

The drawings illustrate an elevational view, with parts in section, of a steam drying installation for paper making machine driers.

The reference numeral 1 indicates a steam drying cylinder of the usual type found on paper machines, said cylinder comprising a hollow drum provided with a hollow trunnion 2 at its rear end for the admission of steam. The removal of the condensate

formed inside the drier drum 1 is suitably accomplished by means of a curved siphon pipe 3 which extends from a point adjacent the lower portion of said drum 1 out through the extended trunnion 2 and separate therefrom to an end fitting 4. The removal of the condensate is, of course, effected by virtue of a steam pressure maintained within the drier drum 1; and is continuously accomplished throughout the drying operation. In place of the siphon 3 any other standard condensate removing device may be employed, such as the bucket type sometimes used on paper machines.

The steam is supplied to the drying cylinder 1 preferably from two sources, a high pressure steam header 5 and a low pressure supply header 6. The low pressure steam ordinarily is obtained from the exhaust of steam engines, turbines and the like used in other operations in the paper mill, the object being to use as much low pressure steam as possible in order to reduce the cost of steam for the drying operation. At the same time, it is necessary in order to obtain an efficient transfer of heat from the steam to the drying cylinder to provide a rapid circulation of the steam through the drying cylinder. In order to accomplish both of these ends, I employ a jet compressor 7 in the inlet steam line 8 communicating with the high pressure steam header 5 and with the hollow trunnion 2. I join the low pressure steam header 6 to said jet compressor 7 by means of piping 9. The purpose of the jet compressor 7 is to effect a high velocity of steam with the use of small quantities of high pressure steam and further to create a suction for drawing into the inlet line 8 low pressure steam from the header 6 at the required rate.

The jet compressor 7 comprises an outer shell 10 flanged at both ends as at 11 and provided with an intermediate globular portion 12 having a side aperture 13. Said aperture 13 is threaded to receive one end of the pipe 9 leading from the low pressure steam header 6. An inner conical shell 14 is adapted to be removably positioned within the lower end of said jet compressor 7 and for this purpose is provided with an end flange 15 adapted to seat in an annular recess formed in the lower flanged end 11. Said conical shell 14 is provided with a constricted orifice 16 in its reduced end, said end terminating adjacent the side aperture

13. A similar, though preferably longer, inner conical shell 17 is adapted to be fitted within the other end of said outer shell 10 with its flanged end 18 similarly positioned within a recess formed in the upper flanged end 11. Said conical shell 17 also terminates in a reduced end having an orifice 19 spaced apart a short distance from the orifice 16 and directly in line therewith. Lugs 20 formed on the inside of the outer shell 10 serve to position the removable conical shells 14 and 17. Said shells 14 and 17 are made removable in order that shells having the required size of orifice 16 and 19 may be quickly installed to meet the demands of the particular drying system on which the jet compressor is to be used. Gaskets 21 may suitably be provided for each end of the shell 10 to form a tight joint between the flanged ends 11 of said shell and flanged fittings 22 on the piping 8, said flanges and fittings being secured together by means of bolts 23.

14. Adjacent to the jet compressor 7 there is provided a Venturi circulator 24 connected in said intake line 8. Said Venturi circulator 24 is similar in construction to the compressor 7 except that its inner shells 25 and 26 are provided with relatively different sized orifices 27 and 28 respectively. The circulator 24 is also provided with a side aperture 29 opposite the orifices 27 and 28 and threaded to receive a pipe 30 which connects said circulator to a side orifice 31 in a nozzle separator 32. Said nozzle separator 32 is positioned in a drain line 33 leading from the fitting 4 to a drain header 34. Said nozzle separator 32 comprises an outer shell 35 provided with flanges 36 at each end adapted to be secured to flanged fittings 37 on the piping 33. A single inner shell 38 extends from the upper end of said outer shell 35 to a point somewhat below the side orifice 31. Said shell 38 is conical shaped and provided with a lower restricted orifice 39. The function of the nozzle separator 32, as is obvious, is to separate the water from the uncondensed steam, the latter being aspirated through the pipe 30 by means of the suction effect created within the Venturi circulator 24. The condensate being, of course, of greater density is delivered through the orifice 39 at a point below the side aperture 31 and therefore tends to continue in its downward path through the piping 33 into the drain header 34. The result is an economy in steam, since little if any uncondensed steam is allowed to pass out into the drain header 34.

15. The operation is substantially as follows: After the steam has passed through the jet compressor 7, it passes through the reduced orifice 27, at which point its velocity is increased and its static pressure decreased to the extent necessary to form a partial vacu-

um sufficient to draw in uncondensed steam from the nozzle separator 32 through the piping 30. The combined streams of steam then pass through the upwardly flared inner shell 26, the velocity being thereby somewhat reduced, and through the piping 8 and the hollow trunnion 2 into the interior of the drying cylinder 1. The pressure of the steam within the drying cylinder 1 forces the condensate formed in the drying process out through the siphon 3 and the steam fitting 4 into the drain line 33. In its passage through the separator 32 the uncondensed steam is separated out from the condensate as described above and the condensate passes on into the drain header and is removed from the system.

16. It is obvious that the sizes of the various orifices in the Venturi fittings must be carefully calculated in order to produce the required velocity of steam to the drier with the required drop in pressure between the separator 32 and the circulator 24. By calculations from suitable charts that may be prepared showing the flow of steam to the drier using various sized orifices, the correct size of orifice for any particular installation of driers may be readily computed. Since the inner shells in the various Venturi fittings are according to my construction interchangeable, it is a simple matter to change the capacity of the system in accordance with varying needs.

17. It will be understood that while I have described my steam circulating apparatus as applied to drying systems for paper machines, said apparatus is equally applicable to any similar drying system, as for instance in the drying of textile fabrics.

18. I am aware that many changes may be made, and numerous details of construction may be varied through a wide range without departing from the principles of this invention, and I therefore do not purpose limiting the patent granted hereon, otherwise than necessitated by the prior art.

19. I claim as my invention:

20. 1. In a steam drying apparatus, a steam drier, a high pressure steam line, piping connecting said line to said drier, a jet compressor and circulator of the Venturi type in said piping, a low pressure steam supply header connected to said jet compressor at the constricted portion, a drain line from said drier, a Venturi type nozzle separator in said drain line and a communicating conduit between said separator and said circulator to recirculate uncondensed steam from said drain line.

21. 2. In a steam drying apparatus, a steam drier, high and low pressure steam lines, piping from said high pressure line to said drier, a jet compressor and a Venturi circulator in said piping, a drain header connected to said drier, a nozzle separator in

said drain connecting line and communicating conduits between said separator and said circulator and between said low pressure steam line and said jet compressor.

5 3. In a paper drier system, a drier drum, high and low pressure steam lines, a jet compressor having a restricted orifice and a side opening adjacent said orifice, said compressor being connected to said high pressure

10 line and to said drier drum, a conduit con-

necting said low pressure line to said side opening, a return drain line, a restriction nozzle in said return drain line, a Venturi circulator in said jet compressor line, and a communicating conduit between said restriction nozzle and said Venturi circulator for recirculating uncondensed steam. 15

In testimony whereof I have hereunto subscribed my name.

JOHN O. WOODSOME.
